My Design for a Trade Mark consists in embossing on a both surfaces of the felted fabric, in a tessellated form, and in addition to the words Lowell Felting Mills, which are in sunken black letters.

The goods to which the Design for a Trade Mark is applied is known as "Hair-Felt Goods," the panels a, of the squares are sunken and the margins b, thereof raised. The letters or words Lowell Felting Mills, are deeply sunken in the felted material, and the entire ornament made in the act of felting the material.

What I claim as my invention and distinct from by Letters Patent, as a Design for a Trade Mark, is, the herein described hair-felt fabric, having a tessellated surface, and words felted in the fabric as set forth.
